CLAIM

The ornamental design for a back support cushion, as shown and described.

DESCRIPTION

FIG. 1 is a top front perspective view of a back support cushion showing my new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof;

FIG. 7 is a bottom plan view thereof;

FIG. 8 is a top rear perspective view thereof;

FIG. 9 is a bottom rear perspective view thereof;

FIG. 10 is a top front perspective view thereof, showing the back support cushion in a position of use with a pair of straps; and,

FIG. 11 is a top front perspective view thereof, showing the back support cushion in a position of use with a pair of straps on a weight bench.

The broken lines showing the straps in FIGS. 10-11 and the bench in FIG. 11 are included for the purpose of illustrating environmental structure and forms no part of the claimed design.

1 Claim, 11 Drawing Sheets
